UNITED STATES PATENT OFFICE.

BYRON B. SHEA, OF KANSAS CITY, MISSOURI.

DESIGN FOR A MENSTRUATOR.

SPECIFICATION forming part of Design No. 30,052, dated January 24, 1899.

Application filed October 21, 1898. Serial No. 694,236. Term of patent 14 years.

To all whom it may concern:

Be it known that I, BYRON B. SHEA, a citizen of the United States of America, residing in Kansas City, in the county of Jackson 5 and State of Missouri, have invented and produced a new and original Design for Menstruators, of which the following is a specification, reference being had therein to the accompanying drawings, forming part thereof.

Figure I is a side elevation view of a menstruator having the configuration or shape embodied in my new design. Fig. II is a front elevation view of the same.

The receiver A of the menstruator has the 15 form of a disk, with flat sides and its periphery rounded. From one side projects radially therefrom a tubular inlet (indicated by B) the outer end of which is bell-mouth shaped. From the opposite side of the disk projects 20 a tubular outlet D, which is surmounted by

a cap E, provided with laterally-projecting flanges F, which are ornamented by knurled edges. Upon one side of the receiver A projects laterally a boss G, which is in the shape of a portion of a sphere, and has through it a 25 transverse hole in which I have shown mounted a ring H. Where the portion B meets the periphery of the disk A it is slightly curved outwardly, so as to form a joint free from sharp angles.

Having thus described my invention, what I claim as new, and desire to secure by Letters Patent, is—

The design for a menstruator, as herein shown and described.

BYRON B. SHEA.
